DESIGN FOR A SPINNING GAME BOARD

Henry Vogelleitner, New York, N. Y.

Application July 9, 1934, Serial No. 52,498

Term of patent 7 years

To all whom it may concern:

Be it known, that I, Henry Vogelleitner, a citizen of Austria, residing at New York city, in the county of New York, and State of New York, have invented a new, original, and ornamental Design for Spinning Game Boards, of which the following is a specification, reference being had to the accompanying drawing, forming part thereof.

Fig. 1 is a plan view of a spinning game board, showing my new design.

Fig. 2 is a perspective rear view of the same.

Fig. 3 is an enlarged perspective front view of the same.

I claim:

The ornamental design for a spinning game board as shown.

In testimony whereof I have affixed my signature.

HENRY VOGELLEITNER.
